(57) **CLAIM**

The ornamental design for an inner ring of a construction drilling cup, as shown.

DESCRIPTION

FIG. 1 is a right view of an inner ring of a construction drilling cup showing my new design;

FIG. 2 is a left view thereof;

FIG. 3 is a front view thereof;

FIG. 4 is a back view thereof;

FIG. 5 is a perspective thereof; and,

FIG. 6 is a perspective thereof.

1 Claim, 6 Drawing Sheets
